UNITED STATES PATENT OFFICE.

AAGE E. WINCKLER, OF MILWAUKEE, WISCONSIN.

FUEL INJECTOR FOR INTERNAL-COMBUSTION ENGINES.

Application filed March 26, 1925. Serial No. 18,381.

The invention relates to devices for injecting fuel into internal combustion engines.

One object of the invention is to provide an improved fuel injector which can be readily attached to and detached from the cylinder head of an internal combustion engine. Another object is to provide an improved construction in which packings, relatively to which the valve and its stem are movable, are avoided, so as to prevent any variation in the injection pressure as a result of variation in frictional retardation to the movement of the valve. Another object of the invention is to provide an improved construction in which provision is made for readily and accurately adjusting the stroke of the valve to correspondingly vary the volume of fuel injected. Other objects of the invention will appear from the detailed description.

The invention consists in the several novel features hereinafter set forth and more particularly defined by the claims at the conclusion hereof.

In the drawings: Fig. 1 is a longitudinal section of a fuel injector embodying the invention and an internal combustion engine to which the injector is applied. Fig. 2 is a detail perspective of the pressure operated fuel valve. Fig. 3 is a detail section of the valve stem showing the ports through which the fuel is conducted from one side of the diaphragm to the other. Fig. 4 is a section of the fuel injector taken at right angles to Fig. 1. Fig. 5 is a detail section through the connection with the fuel delivery plug and the sleeve secured to the valve stem. Fig. 6 is a section on line 6—6 of Fig. 4. Fig. 7 is a section taken on line 7—7 of Fig. 4. Fig. 8 is a section taken on line 8—8 of Fig. 4. Fig. 9 is a sectional perspective of the ring for clamping the margin of the diaphragm to the valve casting. Fig. 10 is a perspective of one section of the housing surrounding the upper end of the valve stem and for supporting the adjustable stop for the valve. Fig. 11 is a sectional perspective of the movable seat for the needle point on the valve. Fig. 12 is a perspective of the bushing to which the stop is threaded.

The invention is exemplified in a fuel injector D which is applied to an engine of the fuel injection type comprising a cyl-

inder b⁴ provided with an outer wall b⁵ to form a water jacket b⁶ around the cylinder and a cylinder-head C which is secured to the cylinder casting by bolts c. Head C comprises an annular or cylindrical wall c', which extends longitudinally into the cylinder b⁴; an inner end c⁵, which is inclined inwardly and upwardly and formed with an opening c⁶; a combustion chamber c⁷ formed in a wall extending upwardly from the end c⁵ and a cylindrical portion c¹⁸ in which the injector D is secured.

The engine is of the four-cycle sleeve-valve type and comprises an outer cylindrical sleeve-valve 25 which fits in the cylinder b⁴ and an inner cylindrical sleeve valve 32 working between sleeve 25 and the wall c' of the cylinder-head C. These sleeves are operated from the engine shaft to control the admission of air to the cylinder and the exhaust of the products of combustion therefrom. Sleeve 25 is provided with a port 30 adapted to register with the air-intake port b⁷ in the cylinder b⁴ and with a port 31 adapted to register with the exhaust port b⁸. Sleeve 32 is provided with an air inlet port 36 which is adapted to register with ports 30 and b⁷ to admit air into the cylinder every fourth stroke. Sleeve 32 is also provided with a port 37 which, during every fourth cycle of the piston, is adapted to register with the exhaust port 31 in sleeve 25 and with an exhaust port b⁸ in the cylinder. Packing rings c² are provided in the wall c' of the cylinder head C to prevent the escape of fluid from the cylinder. A working piston b¹⁸, connected to the crank shaft of the engine by means of the usual pitman (not shown), is mounted to slide in the sleeve 32. A tip c¹⁵ projects from the upper end of the piston and is adapted to enter the combustion-chamber c⁷. The cylinder-head C is water-cooled and is in communication with the water circulating in the water jacket b⁶. The top closure for the water jacket in the cylinder head C is formed by a head E which is fitted to the margin of the cylinder casting. A gasket e', held in a marginal groove in the head E, is clamped downwardly by said head and against the top of the cylinder casting by a collar e⁸ which is screw-threaded to the upper end of the cylindrical extension c¹⁸ and engages a ring e⁴. Ring e⁴ is adapted to compress a gasket e'' around extension c¹⁸ to form a fluid-tight joint between

100

105

110

the head E and said extension. The heads of screws 72, which are threaded to the head E, enter sockets in the ring e^4 to hold the latter against rotation, but permit it to be 5 jammed against the packing e'' by the collar e^8 , so that the head E will be securely held on the cylinder casing.

Fuel injector D is removable and replaceable as a unit and comprises a tubular casing 10 d which extends and fits into the extension c^{13} of the cylinder head C and is provided at its upper end with an outwardly extending flange d' . A valve d^2 , for controlling the injection of fuel into the combustion 15 chamber, comprises a stem portion d^3 which is longitudinally grooved to permit fuel to flow to its point d^6 which is adapted to close against a conical seat d^5 in a nozzle d^4 . This nozzle is formed to spray and separate 20 the fuel as it is injected into the combustion chamber, as well understood in the art. Nozzle d^4 is separately formed from the casing d to permit its replacement in the event of wear, and for this purpose it is provided 25 with a flange d^{40} which is clamped against the lower end of the casing d by a sleeve d^7 which engages said flange, fits around the lower constricted portion of casing d and is held to clamp said flange by an internally 30 screw-threaded collar d^{30} which is threaded to the casing and to the upper end of said sleeve so that the sleeve may be drawn upwardly to clamp the nozzle in place. The faces of flange d^{40} are tapered so that when 35 they are clamped between the casing d and the sleeve d^7 , a fluid-tight joint will be formed to prevent the escape of fuel around the nozzle.

A diaphragm d^9 has its outer margin 40 clamped between the flange d'' of casing d and an annular member d^{12} , which is removably secured to said flange by bolts d^{14} . The inner margin of said diaphragm is clamped between a conoidal seat d^{10} on an 45 annular shoulder or enlargement 49 on the valve stem and a tapered bearing surface d^{11} formed on the lower end of a sleeve d^8 which is movable with the valve. The sleeve d^8 is forced into clamping relation with the 50 diaphragm by a nut 52 which is threaded to a reduced threaded upper portion 53 of the valve stem and is adapted to engage washers for compressing a packing gasket 51 against the upper end of sleeve d^8 . A 55 lock-nut $52'$ is adapted to secure the nut 52 in its assigned position. Gasket 51 forms a fluid-tight joint which prevents the escape of fuel around the upper end of the valve stem. A chamber 48 is formed adjacent the under- 60 side of the diaphragm d^9 to expose the lower face of the diaphragm to fuel under pressure so that when the desired injection pressure is reached, the valve will be opened to inject a charge of fuel into the combustion 65 chamber.

Member d^{12} forms a housing for a spring d^{15} , the force of which is applied to resist the movement of the diaphragm until a predetermined pressure is reached in the fuel line. The upper end of this spring engages 70 an inwardly extending flange d^{16} on member d^{12} and its lower end engages an annular shoulder d^{17} on a collar d^{18} which is screw-threaded to the lower end of the valve sleeve d^8 .

Sleeve d^8 is provided with an offset d^{19} in which is formed a conoidal seat d^{20} for a tapered plug d^{21} , which is connected by a flexible pipe d^{22} to a suitable fuel pumping and metering unit, such, for example, as that set forth in my application filed May 25, 1925, Serial No. 32,550. This plug is removably held in said socket by a cap d^{23} which is threaded to the outer end of the plug and is adapted to clamp a locating 85 washer against the outer end of offset d^{19} . A check-valve 38 , normally closed by a spring 39 , is mounted in plug d^{21} to prevent back flow of fuel. A plug $39'$, which forms a fluid tight joint and a stop for valve 38 , is provided in the outer end of plug d^{21} . A collar 76 is threaded to the plug d^{21} and is adapted to bear against one end of the offset d^{19} to forcibly withdraw the plug from the sleeve d^8 when it is desired to disconnect the fuel line from the fuel injector.

From the check-valve 38 , the fuel passes into a chamber 41 in plug d^{21} and thence downwardly through an inclined port 42 to an annular groove 43 in the valve stem. A locating washer d^{24} is adapted to assure the alignment of the portions of the passageway 42 . Valve stem is longitudinally grooved, as at 44 , to conduct fuel to an 105 annular groove 45 in the lower end of sleeve d^8 adjacent the top of the diaphragm d^9 . An inclined cross-port 46 (Fig. 3) extends through the valve stem above the shoulder 49 and the diaphragm and downwardly divergent ports 47 extend from the central portion of port 46 to the chamber or space 48 below the diaphragm d^9 . Branch ports $47'$ lead laterally from the ports 47 . A groove 50 is formed in the stem of valve d^2 , 110 so that fuel will flow from chamber 48 longitudinally of the grooved portion d^3 of the valve stem to the point d^6 of the valve and the nozzle d^4 . A characteristic of this construction is that the connection between the 115 fuel feed line and the valve, exemplified by the sleeve d^8 , moves vertically with the valve stem and, therefore, the movement of the valve is not retarded by packings or stuffing boxes which are likely to vary the frictional retardation to the movement of the valve and thus correspondingly vary the pressure at which injection occurs. Another characteristic is that the entire fuel line from the pipe d^{22} is descending, so that no

air bubbles will be trapped and the presence of a substantially solid incompressible fuel column will be present at all times.

A coupling ring 64 is adapted to connect the entire injector unit to the collar e^4 so that the injector may be uncoupled from and coupled to the cylinder head C, as a unit. This ring 64 is screw-threaded to ring e^4 and has an annular shoulder 65 to bear against the flange d' on the upper end of the casing d. Openings 66 are formed in the upper end of said coupling ring for the insertion of a tool for turning it. A ring 67 is confined in the coupling ring 64 above a shoulder 68, so that when the injector is being removed, the ring 64 will engage the ring 67 to forcibly withdraw the casing d and the parts sustained thereby from the cylinder head. Screws 70 in casing d are adapted to enter notches 71 in the upper end of extension c^{13} on the cylinder-head C to secure said casing against rotation with ring 64. The nozzle retaining sleeve d^7 is provided with a tapered shoulder 73 which engages a corresponding seat 74 in the extension c^{13} of the cylinder-head C to form a fluid-tight connection between them. The coupling ring 64, engaging the flange d' , jams the casing d downwardly in said extension to maintain a fluid-tight fit between shoulder 73 and seat 74. This connection is made without relative rotation between the shoulder and said seat, because the valve casing is held against rotation during the operation of the coupling ring in applying or removing the injector unit.

The upper end of the valve stem is formed at 55 to serve as an abutment to engage an adjustable stop screw 56 to limit the range of movement of the valve stem and correspondingly vary the volume of the charge of fuel injected during each opening of the valve. Stop screw 56 is threaded to a sleeve or bushing 61 which is supported in and confined against vertical movement by a housing formed of sections 57 and 57'. The sections of this housing are removably secured together by bolts 58 and are formed adjacent their lower ends with an annular groove 59 to receive an annular rib 60 on the member d^{12} . This rib and groove connection removably supports the housing section. Ring 67 is confined in the coupling ring 64 by the housing sections 57, 57'. Bushing 61 is split and provided with a screw 61^a, so that it may be clamped to the screw-thread 53 on the valve stem to prevent accidental displacement. The bushing is held in a predetermined position in the housing sections 57, 57' by a pin 61^b which enters a socket in the bushing. A thumb-wheel 62 is fixed to the upper end of stop-screw 56 and a leaf-spring 63 is adapted to engage the serrated edges of said wheel to yieldingly hold it in its assigned position

during adjustment thereof. This adjustable stop device for the injection valve is exteriorly disposed so that it is readily adjustable at all times.

In operation, the charges of fuel pumped through the pipe d^{22} will be forced past check-valve 38 through chamber 41 and port 42 to groove 43 in the valve stem. Thence, the fuel will flow around the grooved portion 44 of the valve stem and through the inclined cross-port 46 and the ports 47, 47' to the chamber 48 from which it will flow through the grooved portion d^3 of the valve stem to the nozzle d^4 . The fuel in chamber 48, when it is subjected to the predetermined pressure desired, will act against the diaphragm d^9 and against the force of spring d^{15} and open the needle valve to inject a charge of fuel into the combustion chamber of the cylinder.

When it is desired to disconnect the injector unit from the cylinder, it is only necessary to turn the coupling ring 64. The rotation of this ring will act against washer 67 and forcibly withdraw the unit from the cylinder head C, without requiring the removal of the head E in which the water jacket is formed. In replacing the unit, the coupling ring will act against the flange d' and force it into fluid-tight fit with the cylinder head at shoulder 73 and seat 74. When the unit had been disconnected from the cylinder head, the nozzle d^4 may be readily replaced when desired. The stroke of the injection valve may be readily varied by first loosening the screw 61^a to render the stop-screw 56 rotatable in the bushing 61 and then turning the thumb-wheel 62 to correspondingly adjust its lower end to or from the abutment 55 on the valve stem. This adjustment may be effected without removing any parts of the injector unit, the provision of a fuel supply connection which is connected to and movable with the valve stem making this possible. The housing, which supports the stop screw, may be readily removed when desired by removing the bolts 58.

The injector described exemplifies one which may be readily coupled to and uncoupled from a cylinder head; which may be readily assembled and disassembled; in which the valve moves with the connections which deliver fuel to it so that it will be possible to avoid frictional retardation by packings which are likely to prevent the desired synchronism of injection and the injection of equal quantities of fuel are avoided. The fuel ports are of downward trend so as to avoid air bubbles in the fuel supplied to the combustion chamber. Effective provision is made against leakage of fuel, notwithstanding the ready separability of the parts. The injector is adapted for use in multi-cylinder engines in which the

desired synchronism of injection and the injection of equal quantities of fuel are important factors in the efficiency of the engine.

The invention is not to be understood as restricted to the details set forth, since these may be modified within the scope of the appended claims, without departing from the spirit and scope of the invention.

10 Having thus described the invention, what I claim as new and desire to secure by Letters Patent, is:

1. In a fuel injector for internal combustion engines, the combination of an injection valve provided with a stem, a casing in which said valve-stem is slidably mounted for delivering fuel into the combustion chamber of an engine, means operable by the pressure of the fuel, for operating the valve, 15 a sleeve disposed outside of the casing and extending around and fixed to move with the valve-stem, and fuel delivering means connected to the sleeve, and means forming a fuel passage between the sleeve and the 20 valve for conducting fuel from the delivering means to the casing.

2. In a fuel injector for internal combustion engines, the combination of an injection valve provided with a stem, a casing in 30 which said valve is movably mounted, for delivering fuel into the combustion chamber of an engine, a diaphragm operable by fuel under pressure to operate the valve, a sleeve disposed outside of the casing and extending 35 around and fixed to move with the valve-stem, a pipe connection for delivering fuel to the sleeve, movable therewith, and means forming a fuel passage between the sleeve and the valve for delivering fuel from the 40 sleeve to the casing.

3. In a fuel injector for internal combustion engines, the combination of an injection valve provided with a stem, a casing in which said valve-stem is slidably mounted, for 45 delivering fuel into the combustion chamber of an engine, a diaphragm operable by the pressure of the fuel for opening the valve, means for securing the casing to the head of an engine, a sleeve disposed outside 50 of the casing and extending around and fixed to move with the valve stem, a spring around the sleeve for closing the valve, a pipe connection for delivering fuel to the sleeve and means for delivering fuel from 55 the sleeve to the casing.

4. In a fuel injector for internal combustion engines, the combination of an injection valve provided with a stem, a casing in which said valve is slidably mounted, for 60 delivering fuel into the combustion chamber of an engine, a diaphragm having its outer margin clamped to the casing, a sleeve fixedly held on the valve and clamping the inner margin of the diaphragm to the valve-stem, and a connection for delivering fuel to the 65

sleeve, the valve stem being provided with ports for conducting fuel from the sleeve to one side of the diaphragm to operate the valve, and a spring for closing the valve.

5. In a fuel injector for internal combustion engines, the combination of an injection valve provided with a stem having a shoulder thereon, a casing in which said valve is movably mounted, for delivering fuel into the combustion chamber of an 70 engine, a diaphragm having its outer margin clamped to the casing, a sleeve fixedly held on the valve and clamping the inner margin of the diaphragm against said shoulder, a connection for delivering fuel to the sleeve, the valve-stem being provided with ports for 75 conducting fuel from the sleeve to one side of the diaphragm to operate the valve, and a spring for closing the valve.

6. In a fuel injector for internal combustion engines, the combination of an injection valve provided with a stem, a casing in which said valve is movably mounted, for delivering fuel into the combustion chamber of an engine, a diaphragm, a member outside of 80 said casing for clamping the outer margin of the diaphragm thereto, a sleeve fixedly held on the valve stem, a spring between the sleeve and said member for closing the valve, means for delivering fuel to the 85 sleeve, and means for delivering fuel from the sleeve through the stem and diaphragm and into the casing for delivery into the combustion chamber.

7. In a fuel injector for internal combustion engines, the combination of an injection valve provided with a stem, a non-rotatable casing in which said valve is movably mounted, for delivering fuel into the combustion chamber of an engine, a coupling 100 ring for securing the casing in a cylinder head, and means whereby rotation of the ring will positively effect the withdrawal of the casing from the head.

8. In a fuel injector for internal combustion engines, the combination of an injection valve, a non-rotatable casing in which said valve is movably mounted, for delivering fuel to the combustion chamber of an engine, a coupling ring for securing the casing in a cylinder head, means whereby rotation of the ring will positively effect the withdrawal of the casing from the head, comprising a shoulder on the coupling ring and a ring removably connected to the casing. 110

9. In a fuel injector for internal combustion engines, the combination of an injection valve, a non-rotatable casing in which said valve is movably mounted, for delivering fuel to the combustion chamber of an engine, a diaphragm, a member for clamping the diaphragm to the casing, a rotatable coupling ring for securing the casing in a cylinder head, and means whereby rotation of the ring will positively effect the with- 125 130

drawal of the casing from the head, comprising a ring around said member and engaged by the coupling ring.

10. In a fuel injector for internal combustion engines, the combination of an injection valve provided with a stem, a casing in which said valve-stem is movably mounted for delivering fuel to the combustion chamber of an engine, a housing formed 15 of laterally separable sections and supported by the casing, and an adjusting device outside of the casing for limiting the stroke of the valve, carried by the housing.

11. In a fuel injector for internal combustion engines, the combination of an injection valve provided with a stem, a casing in which said valve-stem is slidably mounted, for delivering fuel to the combustion chamber of an engine, a diaphragm for operating the valve, a member for clamping the diaphragm onto the casing, a housing formed of laterally separable sections and removably supported by said member, and an adjusting device outside of the casing 25 for limiting the stroke of the valve-stem carried by the housing.

12. In a fuel injector for internal combustion engines, the combination of an injection valve provided with a stem, a casing 30 in which the valve-stem is slidably mounted for delivering fuel into the combustion chamber of an engine, a sleeve fixedly secured to said valve-stem and provided with an offset, means operable by the pressure of the fuel for opening the valve, means connected to supply fuel to the sleeve comprising a plug extending through said offset, and means for conducting fuel from the sleeve to the casing.

40 13. In a fuel injector for internal combustion engines, the combination of an in-

jection valve provided with a stem, a casing in which the valve stem is slidably mounted, for delivering fuel to the combustion chamber, said valve-stem being provided with a 45 shoulder, a diaphragm, means for clamping the outer margin of the diaphragm to the casing, a sleeve mounted around the valve-stem, and means on the outer end of the valve-stem for clamping the sleeve to secure 50 the diaphragm against said shoulder.

14. In a fuel injector for internal combustion engines, the combination of an injection valve provided with a stem, a casing in which the valve stem is slidably mounted 55 for delivering fuel to the combustion chamber, said valve-stem being provided with a shoulder, a diaphragm, means for clamping the outer margin of the diaphragm to the casing, a sleeve mounted around the valve- 60 stem, means on the outer end of the valve-stem for clamping the sleeve to secure the diaphragm against said shoulder, and a stop-device accessible from the outside of the casing for engaging the end of the stem to 65 limit the movement of the valve.

15. In a fuel injector for internal combustion engines, the combination with a cylinder head provided with a cylindrical extension and a supplemental head through 70 which the extension passes, of a ring non-rotatably held on the supplemental head, a packing between said ring and supplemental head, a nut for forcing said ring towards the supplemental head, an injector comprising a 75 casing and an injection valve therein, a coupling ring screw-threaded to the non-rotatable ring, and means for delivering fuel under pressure to the casing.

Signed at Chicago, Illinois, this 24th day 80 of March, 1925.

AAGE E. WINCKLER.
